UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRIC SWITCH.

1,426,811.

Specification of Letters Patent. Patented Aug. 22, 1922.

Application filed June 26, 1919. Serial No. 306,783.

To all whom it may concern:

Be it known that I, REUBEN B. BENJAMIN, a citizen of the United States, residing at Chicago, in the county of Cook and State of Illinois, have invented new and useful Improvements in Electric Switches, of which the following is a full, clear, concise, and exact description, reference being had to the accompanying drawing, forming a part of this specification.

My invention relates to electric switches and more specifically to pull snap switch sockets.

One of the objects of my invention is to provide such a device which will be simple in construction, cheap to manufacture and durable and efficient in use.

A further object of my invention is to provide an improved compact pull snap switch mechanism which can be conveniently located in a socket.

Further objects will appear from the detailed description to follow and from the appended claims.

25 In the drawings in which one embodiment of my invention is shown:

Fig. 1 is a side elevation of a pull snap switch socket embodying my invention, parts being broken away to show the interior construction;

Fig. 2 is a plan view of the socket with the cap removed;

Fig. 3 is a section on the line 3—3 of Fig. 2, the switch mechanism being shown in elevation;

Fig. 4 is also a section on the line 3—3 of Fig. 2, the switch mechanism however being shown in section;

Fig. 5 is a section on the line 5—5 of Fig. 4 looking in the direction of the arrows;

Fig. 6 is a section on the line 6—6 of Fig. 4 looking in the direction of the arrows;

Fig. 7 is a fragmentary view of the lower portion of the socket showing part of the shade support and shade;

Fig. 8 is a side elevation of the socket and part of the shade and holder, parts being broken away to show the interior construction;

Fig. 9 is a fragmentary sectional view showing part of the switch socket;

Fig. 10 is an exploded view showing the connection for the pull chain;

Fig. 11 is an exploded view showing the switch shaft and associated parts;

Fig. 12 is a perspective view of a sleeve which separates the two springs;

Fig. 13 is a side view of the ratchet-member;

Fig. 14 is a plan view of the shade holder; 60 and

Fig. 15 is a bottom plan view of the socket.

In order to give a general idea of the invention it is here stated that the switch mechanism shown is of the ratchet snap 65 type, that is to say, the switch mechanism is actuated by a pull member, which operates the ratchet, so that a pull on the switch will throw the switch to closed position, and the succeeding pull on the switch will throw the 70 switch to open position, and in which the switch mechanism is provided with a releasable detent, which holds the switch mechanism until a considerable spring pressure has been accumulated, and then releases 75 the switch mechanism.

In such switch mechanisms, two springs are usually provided, one for returning the ratchet after it has been operated by the pull chain, and one for accumulating pressure to cause the snap action of the switch. 80

In the embodiment of my invention shown I use for these two springs, two coil torsion springs, one being located inside the other, whereby compact construction is secured. 85

Referring now to the drawings in detail, the pull snap switch socket shown comprises an insulating base 20 for supporting the receptacle contacts and switch mechanism, and a cap 21 of insulating material for housing 90 the switch mechanism and supporting the wiring terminals. The insulating base 20 is provided with a cylindrical recess 22 in its outer end for accommodating the receptacle contacts, and is also provided with a recess 23 in its inner end for accommodating the switch mechanism.

The threaded shell contact 24 is electrically connected with one of the wiring terminals 25 by means of a screw 26 extending 100 through a flange at the inner end of the threaded shell contact, through registering apertures in the insulating base 20 and cap 21, and threaded into the plate 27 into which the binding screw of the wiring terminal 25 105 is screwed.

The switch mechanism 29 controls the circuit, the binding screw of the wiring terminal 25 and the center contact 31. This other wiring terminal 25 is electrically connected with 110

one of the brushes 32 of the switch mechanism, and the center contact 31 is electrically connected with the other brush 33 of the switch mechanism (Figs. 3, 4 and 6).
5 The brush 32 is secured to the insulating base 20 by means of a metal eyelet 34 and is electrically connected with the wiring terminal 30 by means of a screw 35 which extends through the eyelet 34 and is threaded into the plate 36 into which the binding screw 37 of the wiring terminal 30 is screwed.

The center contact 31 is held in place on the base 20 and electrically connected with the brush 33 by means of a screw 38, extending through registering openings in the brush 33, the insulating base 20, and the center contact 31, and having a nut 39 threaded onto its end. A disc 40 of insulating material such as fibre is held in place 20 between the insulating base and the insulating cap 21, this serving to keep any loose strands of the feed-wires 41 and 42 from coming in contact with the switch mechanism. The screws 26 and 35 not only serve 25 as electrical conductors, but also serve to hold the insulating base 20 and cap 21 together. The screw 26 also serves to hold the threaded shell contact 24 in position on the base 20.

30 The switch mechanism which controls the circuit between the two brushes 32 and 33 comprises a U-shaped switch frame 43 which may be of sheet-metal stamping, a U-shaped bridging plate 44, which may also be a sheet-metal stamping, which in one position electrically connects the brushes 32 and 33 and in another position leaves them electrically disconnected, a switch shaft 45 rotatably mounted in the switch frame 43, a 40 trip-plate 46 connected to rotate with the bridge-plate 44, an eccentric 47 rotatable with the switch shaft 45 for actuating the trip-plate 46 to release it when the spring pressure has sufficiently accumulated, a 45 ratchet driven member 48 secured to the shaft 45 to rotate the latter, a coil torsion spring 49 having one end connected to the ratchet driven member 48 and the other end connected to the bridge-plate, for accumulating pressure to cause the snap action of the bridging-member 44, a switch lever 50 having ratchet teeth 51 for driving the ratchet driven member 48, a pull-chain 52 for actuating the switch lever 50 and a coil torsion spring 53 having one end connected to the U-shaped frame 43, and the other end connected to the switch lever 50, this coil torsion spring serving to return the switch lever after it has been actuated by the pull 50 chain 52.

The switch frame 43 has a base portion 54 secured to the insulating base by means of screws 55 and has two standard portions 56 and 57 respectively, in which the journal portions 58 and 59 of the switch shaft

45 are rotatably mounted. The standard portion 56 is provided with four stop projections 59' which cooperate with a lug or projection 60 on the trip-plate 46 to hold this trip-plate 46 from rotation under the 70 accumulating spring pressure until this trip-plate is moved by the eccentric 47 to a position in which the lug 60 is free from that one of the lugs 59' with which it is engaged. The trip-plate 46 is actuated to 75 release the lug 60 from engagement with one of the lugs 59' by means of the eccentric 47 which works in the opening 61 of the trip-plate. This eccentric 47 is secured to rotate with the switch 45 by means of a slot 80 62 (Fig. 11) which engages with a flat portion 63 of the shaft 45. The trip-plate 46 is connected to rotate with the bridge-plate 44 by means of a lug 64 stuck up from the trip-plate 46 which works in a notch or 85 slot 65 (Fig. 6) in the bridge-plate 44. The relation between the lug 64 and the slot 65 is such that the trip-plate will not permit the bridge-plate to rotate until the lug 60 of the trip-plate is free from the stop 59', 90 but is such that it will permit the eccentric 47 to shift the trip-plate to cause the projection 60 to slide off of the lug 59'. When this takes place the accumulated tension in the torsion spring 49 causes the trip-plate and bridging member to snap through 95 a quarter of a revolution to quickly break the circuit between the binding terminal 36 and the center contact at two points, that is to say, at both of the brushes 32 and 33. 100

The ratchet driven member 48 is connected to rotate the shaft 45 by means of a slot in the ratchet driven member which engages a flattened portion 64 of the shaft 45 (Fig. 11). The switch lever 50 may be 105 formed of a plurality of insulating discs of fibre or other suitable material, which may be held together by an eyelet member 65 which may be formed integral with the ratchet plate which carries the ratchet 110 teeth 51. One end of the the torsion spring 53 which serves to return the switch lever may be secured to this eyelet portion 65 and the other end of said torsion spring may be caught under a lug 66 (Fig. 11) stuck up 115 from the base portion of the U-shaped switch frame. The coil torsion spring 49 which serves to give the snap action to the switch is located inside of and coaxial with respect to the coil torsion spring 53 which 120 serves to return the switch lever. For separating these coil torsion springs from each other, a sheet metal sleeve 66' (Fig. 12) is provided which lies outside of the smaller spring and inside of the larger spring, and 125 one end of which is secured to and supported on a hub or lug portion 66 formed integral with the bridging-plate 44. This sleeve 66 has three lugs 67 stuck up therefrom, which form supporting means for a sheet metal 130

sleeve 68 which houses the outer coil spring 53, and also forms a journal for the switch lever 50, the eyelet portion 65 closely surrounding this sleeve 68 and forming a bearing for the switch lever. The end of the sleeve 68 opposite the end which bears on the lugs 67 is supported by a hub or boss 69, which may be formed integral with the ratchet driven member 48.

- 10 The pull chain 52 is connected to the switch lever by means of a stamped sheet-metal fastener 70 (Figs. 9 and 10) having a pair of hooks or fingers 71, between which the ball of the pull chain is caught and held, 15 and a base portion 72 having laterally extending portions extending into slots 73 (Fig. 9) in the fibre discs of which the switch lever is composed, one of said laterally extending portions also extending into a slot 74 (Fig. 10) formed in the ratchet plate 20 which carries the ratchet teeth 51 (Fig. 18).

Each pull of the pull chain turns the switch lever through a little more than a quarter of a revolution. The motion of the switch lever in the direction in which it is operated by the pull chain is limited by an abutment 75 (Fig. 9) integral with the insulating base 20, which abutment 75 is located in the path of a stop shoulder 76 formed on the switch lever. This movement of the switch arm also causes the ratchet driven member 48 to be rotated through a little more than a quarter of a turn. During about the first 60 degrees of movement of the ratchet driven member, this simply tightens up the coil torsion spring 49, as the bridging member 44 and the trip-plate 46 are held from rotation by the engagement of the lug 60 with one of the lugs 59, the lug 64 on the trip-plate holding the bridging plate 44 from movement. However, after about 60 degrees of rotation of the ratchet driven member, the movement of the eccentric 47 with respect to the trip-plate 46 will shift the trip-plate so as to cause the lug 60 to slip off from the projection 59 with which it is engaged, the relative movement between the trip-plate 46 and the eccentric 47 being such as to cause the lug 60 to engage with the next succeeding stop 59. This movement of the bridging-plate 44 through an arc of 90 degrees will cause the switch to be shifted from the "on" to "off" position.

55 The fact that one of the torsion springs is arranged coaxial with and inside of the other torsion spring makes for compactness of construction, as does also the fact that the switch lever is located between the ratchet driven member and the bridging-plate. This compactness of construction enables the pull snap switch device to be assembled and put in place in the insulating base of a lamp socket with the axis of the 60 switch shaft extending transversely to the

axis of the shell contact of the socket.

The insulating base 20 is provided with a passage 77 leading from the switch chamber 23 to the side of the insulating base to accommodate the pull chain 52, and the 70 side of the insulating base 20 is provided with a groove or channel 78 (Figs. 1, 7 and 8) leading from the passage 77 downwardly to the bottom of the insulating base to permit the pull chain to pass straight down inside of the shade 79 to give a practically straight pull for the chain.

75 The insulating base is provided with an annular groove channel 80 near its lower edge to accommodate a shade holding device 81 (Figs. 7, 8 and 14). This shade holding device 81 comprises a pair of clamping members 82, which may be drawn toward each other by means of clamping screws 83, these clamping members 82 being provided with bent in portions 84 which extend through corresponding openings in a shade holding collar 85, the bent in portions 84 extending into the aforesaid annular groove 24 so that when 90 the clamping members are drawn up these bent in portions 84 will extend through the openings in the shade holding ring 85 and into the annular groove 80 to hold the shade holding ring 85 and the shade 95 99 in position on the socket. In securing the shade holder in position the clamping members 84 are so placed with respect to the insulating base 20 that the pull chain 52 will extend down between two of the bent 100 in portions 84, so that these bent in portions will not interfere with the chain 52 passing down through the channel or groove 78, the depth of this channel or groove 78 is such that it affords a free passage of 105 the chain 52 inside the shade supporting ring 78. The channel 78 at that portion where it crosses the channel 80 is of course more shallow than that portion of the channel 78 above and below the channel 80, but 110 as the bent in portions 84 do not extend into the channel 80 at this point where the channel 78 crosses the channel 80, the clamping members 82 will not interfere with the chain 52. As a matter of fact, the sleeve 115 portion of the shade holding member 85 forms a sort of a covering for the channel 78 so as to house that part of the chain which lies in this channel 78.

What I claim as new and desire to secure 120 by Letters Patent of the United States is:—

1. A switch mechanism comprising an oscillatable operating member, a pull member for actuating said operating member, a coil torsion spring for returning said oscillating member after it has been actuated, a ratchet member actuated by said oscillating member, a rotatable switch contact, a coil torsion spring connecting said ratchet and 125 said rotatable switch member, a releasable 130

- detent for holding said rotatable switch member from rotation to cause energy to be stored in said second torsion spring, one of said coil torsion springs surrounding the other. 5
2. A switch mechanism, comprising an oscillatable operating member, a pull member for actuating said operating member, a coil torsion spring for returning said oscillatable member after it has been operated by said pull member, a ratchet driven by said oscillating member, a rotatable switch member, a second coil torsion spring for transmitting force from said ratchet member to 10 said rotatable switch member, a releasable detent for temporarily holding said rotatable member from rotation, one of said springs surrounding the other, and a sleeve surrounding one of said springs and surrounded by 15 the other for keeping them separate. 20
3. A switch mechanism, comprising an oscillatable member, a pull member for actuating said oscillatable member, a coil torsion spring for returning said oscillatable member after it has been actuated by said pull member, a ratchet member driven by said oscillatable member, a rotatable switch member, a spring for transmitting force from 25 said ratchet member to said rotatable member, a detent for temporarily holding said rotatable member from rotation, and a sleeve surrounding said coil torsion spring on which sleeve said oscillatable member is mounted. 30
4. A switch mechanism, comprising an oscillatable operating member, a pull member for actuating said oscillatable member, a spring for returning said oscillatable member after it has been actuated by said pull member, a ratchet driven by said oscillatable member, a rotatable switch arm, a coil torsion spring for transmitting force from said ratchet to said switch arm, a releasable detent for temporarily holding said switch 35 from rotation to cause energy to be stored in said coil torsion spring, a sleeve surrounding said coil torsion spring, and forming a journal for said oscillatable member. 40
5. A switch mechanism, comprising an oscillatable operating member, a pull member for actuating said oscillatable member, a ratchet driven by said oscillatable member, a rotatable switch arm coaxial with said oscillatable member, a spring for transmitting force from said ratchet to said switch 45 arm, a detent for temporarily holding said switch arm from rotation to cause energy to be stored in said spring; said oscillatable member being located between said ratchet and said switch arm. 50
6. A switch mechanism, comprising an oscillatable member, a ratchet driven by said oscillatable member, a switch arm, said switch arm, ratchet and oscillatable member being coaxially mounted, a coil torsion 55
- spring extending between said ratchet and 65 said rotatable switch arm for transmitting force from said ratchet to said switch arm, a detent for temporarily holding said switch arm from rotation to cause energy to be stored in said coil torsion spring, said oscillatable member being located between said ratchet and switch arm and surrounding said coil torsion spring. 70
7. A switch mechanism, comprising an oscillatable member, a ratchet member 75 driven by said oscillatable member, a rotatable switch arm, said switch arm, ratchet and oscillatable member being coaxially mounted, a coil torsion spring for transmitting force from said ratchet member to said 80 switch arm, a second coil torsion spring for returning said oscillatable member, one of said coil springs surrounding the other, and both of said springs being coaxial with said switch arm, a detent for temporarily holding said switch arm from rotation to cause 85 energy to be stored in said first coil torsion spring, said oscillatable member being located between said ratchet member and said switch arm and surrounding both of 90 said springs. 95
8. A switch socket comprising an insulating support, a threaded shell and center contacts and a switch mechanism supported thereby, said switch mechanism comprising an oscillatable member, a ratchet member driven by said oscillatable member, a rotatable switch arm, a coil torsion spring extending between said ratchet member and said switch arm, for transmitting force from 100 said ratchet member to said switch arm, a releasable detent for temporarily holding said switch arm from rotation, for causing energy to be stored in said coil torsion spring, said switch arm, ratchet member, oscillatable 105 member and torsion spring being coaxially mounted, and the axis extending transversely with respect to the axis of the threaded shell contact. 110
9. A switch socket, comprising an insulating support; a threaded shell and center contact and a switch mechanism supported by said insulating support, an oscillatable member, a ratchet member driven by said oscillatable member, a rotatable switch arm, oscillatable member and ratchet member being coaxially mounted, said oscillatable member being located between said ratchet-member and said rotatable switch arm, the axis of 115 said switch arm, oscillatable member and ratchet member extending transversely with respect to the axis of the threaded shell contact. 120
- In witness whereof, I have hereunto subscribed my name.
- REUBEN B. BENJAMIN.
